LOOM SHUTTLE

Carl D. Brown, Hopedale, Mass., assignor to
Draper Corporation, Hopedale, Mass., a corpora-
tion of Maine

Application January 22, 1935, Serial No. 2,926

10 Claims. (Cl. 139—223)

The present invention pertains to automatically threading loom shuttles and has more particular reference to the filling tensioning or controlling means of such shuttles.

Shuttles of the type to which my invention pertains are employed in automatic bobbin changing looms, wherein the filling supply in the shuttle is automatically replenished by transferring a new filling carrier, such as a bobbin, to the shuttle when required. The shuttles are provided with a threading block whereby the filling becomes partially threaded in the shuttle at the beginning of the first pick after transfer and fully threaded at the beginning of the second pick after transfer. Thus, the running filling, when partially threaded, occupies a given path in the shuttle and threading block, and occupies a relatively different path therein when fully threaded. The path of the partially threaded filling is nearly straight, while the path of the fully threaded filling is more tortuous, with the result that less tension is placed on the filling during the first pick after transfer than during subsequent picks.

The placing of a different tension on the filling during the first pick after transfer than during subsequent picks will cause a substantial defect in the appearance of cloth woven with artificial silk filling such as rayon. It has been thought that in order to prevent such defects it was only necessary to add to the shuttle a tension device which is capable of becoming effective early in the first pick after transfer. Experience has shown that such devices may prevent a slack first pick, but, since their tension is added to the tension placed on the fully threaded filling, all subsequent picks will be placed under too much tension, and thus they may cause more defects than they cure.

I propose to overcome the aforementioned defects by providing, in an automatically threading loom shuttle, a tension device which is capable of engaging and tensioning the running filling only during such time as the filling may be partially threaded, the device releasing the filling as the latter becomes fully threaded. I find that it is not enough merely to apply friction to the filling while the shuttle is in flight, but that the tension device must also be capable of preventing a slackening of the filling during the interval after the shuttle is boxed at the end of the first pick after transfer and before the filling is beaten into the cloth. Accordingly, the present invention provides a tension device which is comprised of relatively movable members, ca-

pable of frictioning or gripping the filling sufficiently to prevent the slackening of the filling as aforesaid.

In the preferred embodiment of my invention herein disclosed the shuttle is provided with a threading block having a thread guard which projects outwardly and rearwardly over a longitudinally extending thread passage. The tension device is conveniently of the spring clamp variety and, in said embodiment, one of the clamp members is comprised of the thread guard which has a friction surface on its underneath side. The other clamp member is shown as being comprised of a spring pressed plunger bearing upwardly against the thread guard, the size and location of the plunger being such as to result in the release of the filling as the latter passes from its partially threaded to its fully threaded position. Such embodiment is disclosed by way of illustration only, as it will be apparent that the results accomplished by the same may be otherwise attained within the scope of the appended claims.

The said preferred embodiment of the invention is illustrated on the accompanying drawing, of which:

Fig. 1 is a perspective view of the eye end of the shuttle, with the filling fully threaded therein;

Fig. 2 is a cross-sectional view taken approximately on line 2—2 of Fig. 4, but with the filling omitted;

Fig. 3 is a cross-sectional view taken approximately on line 3—3 of Fig. 4; and

Fig. 4 is a plan view of the eye end of the shuttle, with the filling partially threaded therein.

The shuttle shown on the drawing includes a shuttle body 1 having a cavity 2 wherein is received a filling carrier as bobbin 3. Suitable conventional means, not shown, are provided for holding the bobbin in such manner that it can be automatically replaced by a fresh bobbin when the filling supply becomes depleted. The shuttle body is recessed to receive a threading block 4 which has front and rear walls 5 and 6 defining a longitudinally extending thread passage 7 which is axially aligned with the bobbin. A thread guard 8 projects from the front wall 5 outwardly and rearwardly over the thread passage and the rearward end of the thread guard is free.

In the operation of the loom (not shown), when a bobbin is first transferred to the shuttle the filling 7 extends from the bobbin longitudinally outwardly of the shuttle above the threading block and is fixed to a holder (not shown). Thereafter the shuttle is picked in a direction

opposite to the direction in which the bobbin points, this being called the first pick after transfer. This first pick, for the shuttle shown, will be toward the left, Figs. 1 and 4. As the shuttle 5 starts this pick, the filling in unwinding from the bobbin swirls about and, with the assistance of a threading scroll 9, becomes engaged beneath the thread guard. The filling then is partially threaded in that it extends from the bobbin 10 through the thread passage 7, beneath the thread guard 8, and longitudinally outwardly to the fixed holder. The filling runs in its partially threaded position throughout the first pick. When the shuttle is started on the second or 15 return pick after transfer the filling slides down the inclined passage 10 into the side delivery eye 11. Thereafter the running filling extends from the bobbin 3 through the thread passage 7 adjacent the bottom of the latter, over bridge 12, thence downwardly and forwardly and 20 through the side delivery eye. The shuttle as thus far described may be similar to that disclosed in patent to E. S. Stimpson, No. 1,483,492 granted Feb. 12, 1924.

It will be noted that the fully threaded filling is frictionally engaged by the bridge 12, a guide 12' and one wall of the side delivery eye 11, wherefore it will be placed under tension. The shuttle as thus far described does not, however, 25 provide for tensioning the partially threaded filling during the first pick after transfer, in which respect it is typical of shuttles employed for weaving with most cotton fillings. It will now be seen that the addition to such shuttles of a 30 tension device which is operative during the first and all subsequent picks after transfer can not provide that uniformity of tension which I find to be essential in weaving with rayon and other artificial silk filling threads.

40. In providing for maintaining the same tension on the filling during the first pick after transfer as during subsequent picks, I have made use of the fact that the running filling occupies a different path in the threading block during said 45 first pick than during the subsequent picks. Accordingly, I add to the shuttle a tension device which is operative only during such time as the filling occupies the first said path, i. e., while it is partially threaded. This tension device may 50 be designed or adjusted to provide the same tension as is provided in the more tortuous path of the fully threaded filling, thereby providing the desired uniformity of tension.

55. The specific tension device shown on the drawing is specifically designed for use with the shuttle and threading block of the aforesaid E. S. Stimpson patent. It is comprised of relatively oppositely movable members, one of which is thread guard 8. The thread guard is provided 60 with a friction surface on its underneath side. This surface may be variously contrived, but I prefer to form the same from a felt pad 13 which is glued to the thread guard. The pad will be firmly anchored in place if a portion of it is pulled 65 through an opening in the threading block as shown at 14, Fig. 2. The rearward edge of the pad may be protected by a down turned end of the thread guard, as shown at 15.

70. The friction member just described is fixed, but the opposed member is made movable. To this end the second member may be comprised of a friction plate 16 which is disposed in a horizontal plane directly below the horizontal pad 13 and is yieldingly urged upwardly into contact with the 75 latter. The plate 16, as shown, is formed on the

upper end of a vertical plunger 17 which is slidably mounted in a bushing 18. The bushing may be adjustably secured in the shuttle body by being threaded into a bore therein. A coiled spring 19 surrounds the plunger and bears between the bushing and plate to urge the latter upwardly. The tension of the spring, and consequently the friction exerted on the filling, may be adjusted by turning the threaded bushing. The forward edge of the plate 16 may be provided with a projection 20 which engages in a notch in the shuttle body to prevent the plate and plunger from rotating.

10. The tension device as thus described, being positioned immediately beneath the free end of the thread guard, and being open rearwardly, will engage the filling as the latter becomes partially threaded. The device is, however, open forwardly, and spaced away from the path of the fully threaded filling. Consequently, as the filling passes downwardly and forwardly through the passage 10 in passing to the side delivery eye (in becoming fully threaded) it will become disengaged from the tension device. In other words, the friction plate 16 will engage the filling and press it against the other friction member only during the first pick after transfer.

15. It has been proposed heretofore to equalize the tension on the first and second picks of filling by adding a brush or bristles to the shuttle body outwardly of the threading block. See, for instance, E. S. Stimpson patent 1,533,224, granted May 19, 1925. Such bristles were found to be incapable of contacting the filling during the whole of the first pick after transfer, and furthermore are incapable of preventing the filling from slackening after the shuttle has boxed at the end of such first pick. The present invention overcomes such difficulties by providing relatively movable friction members which are capable of maintaining friction on the filling during the whole of the first pick after transfer, and even after the shuttle has boxed.

20. It will be apparent to those skilled in the art that changes may be made in the shuttle and threading block and in the construction and location of the tension device, within the scope of the appended claims.

25. Having fully disclosed the preferred embodiment of my invention, I claim:

30. 1. An automatically threading loom shuttle having a threading block wherein the running filling occupies one path during the first pick after transfer and a relatively different path during subsequent picks, and a first pick tension device comprised of opposed, relatively movable thread engaging and tensioning members positioned in the first said path only, said members engaging and tensioning the running filling between them throughout substantially the whole of only the first pick after each transfer.

35. 2. An automatically threading loom shuttle having a threading block wherein the running filling occupies one path during the first pick after transfer and a relatively different path during subsequent picks, and a first pick tension device comprised of opposed members at least one of which is yieldingly urged into cooperation with the other, said members being positioned in the first said path only and engaging and tensioning the running filling only throughout substantially the whole of said first pick after transfer.

40. 3. An automatically threading loom shuttle having a threading block wherein the running filling occupies one path during the first pick after

transfer and a relatively different path during subsequent picks, and a spring clamp tension device positioned in the first said path only and engaging and tensioning the running filling only throughout substantially the whole of said first pick after transfer.

4. An automatically threading loom shuttle having threading delivery means wherein the running filling becomes partially threaded during the first pick after transfer and fully threaded during the next succeeding pick, said shuttle having a first pick tension device comprised of a spring clamp tension engaging and tensioning the partially threaded filling only and releasing the filling as the same becomes fully threaded during the second pick after transfer.

5. An automatically threading loom shuttle having a side delivery eye, a threading block provided with a longitudinally extending thread passage therein, a thread guard extending outwardly and rearwardly over said thread passage, the rearward end of said thread guard being free, and a spring clamp tension device positioned immediately beneath the free end of said thread guard in position to engage and tension the partially threaded filling during the first pick after transfer but to release the filling as it becomes fully threaded during the second pick after transfer.

6. An automatically threading loom shuttle having a side delivery eye, a threading block provided with a longitudinally extending thread passage therein, a thread guard extending outwardly and rearwardly over said thread passage, the rearward end of said thread guard being free and being provided with a friction surface, and a spring pressed friction member engaging the partially threaded filling and pressing the same against said friction surface, said friction member being constructed to become free of engagement with the running filling as the latter passes down into said side eye in becoming fully threaded.

7. An automatically threading loom shuttle having a side delivery eye, a threading block provided with a longitudinally extending thread passage therein, a thread guard extending outwardly and rearwardly over said thread passage, the rearward end of said thread guard being free and being provided with a friction surface on the underneath side thereof, and a yielding friction member engaging the partially threaded filling and pressing the same against said friction surface only during the first pick after transfer, said shuttle being provided with a path leading from said thread passage to said side delivery eye for

receiving the fully threaded filling, said path being spaced away from the thread engaging surface of said friction member whereby the fully threaded filling is free of engagement with said surface.

8. An automatically threading loom shuttle having a side delivery eye, a threading block provided with a longitudinally extending thread passage therein, a thread guard extending outwardly and rearwardly over said thread passage, the rearward end of said thread guard being free and being provided with a friction surface on the underneath side thereof, the running filling during the first pick after transfer extending through said thread passage and longitudinally outwardly of the shuttle beneath said thread guard and passing into said side delivery eye during the second pick after transfer, and a yielding friction plate engaging the filling only during said first pick and pressing the same against said friction surface, said plate being positioned to be free of the filling when the latter passes through said delivery eye.

9. An automatically threading loom shuttle having a side delivery eye, a threading block provided with a longitudinally extending thread passage therein, a thread guard extending outwardly and rearwardly over said thread passage, the rearward end of said thread guard being free, and a spring clamp tension device comprising yieldingly opposed horizontal friction surfaces positioned immediately below the free end of said thread guard, said tension device being open rearwardly to receive the filling as the latter becomes partially threaded and said tension device being open forwardly to permit the filling to become free thereof upon passing into side delivery eye.

10. An automatically threading loom shuttle having a side delivery eye, a threading block provided with a longitudinally extending thread passage therein, a thread guard extending outwardly and rearwardly over said thread passage, the rearward end of said thread guard being free and being provided on its underneath side with a substantially horizontal friction surface, a horizontal friction plate positioned beneath said surface in position to engage the running filling when the latter extends longitudinally outwardly of the shuttle beneath said thread guard but to be free from engagement with the filling when the same extends through said side delivery eye, and means for yieldingly urging said plate upwardly into engagement with said friction surface.
